No. 36,547.

Patented September 8, 1903.

UNITED STATES PATENT OFFICE.

THOMAS J. ANSON, OF AKRON, OHIO.

DESIGN FOR A FLOOR OR WALL COVERING.

SPECIFICATION forming part of Design No. 36,547, dated September 8, 1903.

Application filed August 6, 1903. Serial No. 168,549. Term of patent 14 years.

To all whom it may concern:

Be it known that I, THOMAS J. ANSON, a citizen of the United States, residing at Akron, in the county of Summit and State of Ohio, have invented a new, original, and ornamental Design for Floor or Wall Coverings, of which the following is a specification, reference being had to the accompanying drawing, forming a part hereof.

10. What I claim, and desire to secure by Letters Patent, is—

The ornamental design for a floor or wall covering, as shown.

In testimony whereof I have signed my name to this specification in the presence of 15 two subscribing witnesses.

THOMAS J. ANSON.

In presence of—

C. E. HUMPHREY,
E. W. CASWALL.
